UNITED STATES PATENT OFFICE.

CARL ENGBERG, OF ST. JOSEPH, MICHIGAN, ASSIGNOR TO JOHN W. MULLEN
AND ABEL W. WELLS, OF SAME PLACE.

DESIGN FOR A BOX-BLANK.

SPECIFICATION forming part of Design No. 34,064, dated February 12, 1901.

Application filed January 15, 1901. Serial No. 43,423. Term of patent 14 years.

To all whom it may concern:

Be it known that I, CARL ENGBERG, a citizen of the United States, and a resident of St. Joseph, in the county of Berrien and State of Michigan, have invented and produced a new and original Design for a Box-Blank, of which the following is a full, clear, and exact description.

Reference is to be had to the accompanying drawing, forming a part of this specification, in which the figure is a plan view of a box-blank, showing my design.

The leading feature of the design consists in the configuration of the box-blank made the subject of the accompanying illustration.

The design in its entirety consists of a center-piece A, from the edges of which extend flaps B B' B² B³, of which the flaps B² B³ appear with wide flanges C C' and C' C', reaching to the side edges of the flaps B B', and the outer ends of said flaps appear with nar-

row bands D D', extending throughout the length of said outer ends and a short distance upon the flanges C C' and C' C', the joints of the center-piece A and the flaps B B' B² B³ appearing as creases, with similar creases forming the joints between the flaps B² B³ and their flanges C C' and C' C', and a crease appearing between the bands D D' and the adjacent parts.

Having thus fully described my invention, I claim as new and desire to secure by Letters Patent—

The design for the box-blank herein shown and described.

In testimony whereof I have signed my name to this specification in the presence of two subscribing witnesses.

CARL ENGBERG.
